UNITED STATES PATENT OFFICE.

GIOVANNI RACCAGNI, OF BRIDGEPORT, CONNECTICUT.

RAILWAY-TIE AND RAIL-FASTENER.

1,274,592.

Specification of Letters Patent.

Patented Aug. 6, 1918.

Application filed December 6, 1917. Serial No. 205,781.

To all whom it may concern:

Be it known that I, GIOVANNI RACCAGNI, a subject of the King of Italy, residing at Bridgeport, in the county of Fairfield and State of Connecticut, have invented certain new and useful Improvements in Railway-Ties and Rail-Fasteners, of which the following is a specification.

This invention relates to certain new and useful improvements in railway tie and rail fasteners.

The primary object of the invention is the provision of a railway tie preferably formed of metal and arranged with readily locked railway rails in suitably spaced relations thereon without the employment of the usual detached fasteners such as screws and bolts, the structure possessing great strength and durability.

A further object of the device is the provision of a metallic railway tie that is easy and inexpensive to manufacture, arranged for preventing water from collecting therein and having readily operable locking means for rails for holding the latter transversely positioned upon the tie at the proper distance apart for forming a track.

A still further object of the invention is the provision of a tie adapted for mounting railway rails thereon and so arranged that the rails may be locked or unlocked from points adjacent the opposite ends of the tie.

In the drawing forming a part of this application and in which like designating characters refer to corresponding parts throughout the several views.

Figure 1 is a side elevation of my form of tie partially broken away having two rails shown in transverse section operatively locked thereon.

Fig. 2 is a top plan view thereof.

Fig. 3 is an end view of the same showing two ties in their operative positions, one of the same being shown in vertical transverse section.

Fig. 4 is a vertical longitudinal sectional view through the end portion of a tie having the rail mounted thereon with the locking member released, and

Fig. 5 is a perspective view of one of the bearing blocks employed.

My railway tie in its preferred embodiment broadly consists of a metal body 10, rectangular in cross section, of substantially the usual dimensions of an ordinary tie but preferably being hollow with a chamber

11 extending substantially throughout the length thereof open at the bottom of the tie as at 12 with longitudinal slots 13 communicating with the said chamber adjacent the opposite ends of the top 14 of the said body. A transversely arranged rib 15 is arranged upon the top of the body 10 spaced inwardly of each of the slots 13 a sufficient distance for receiving the bases 16 of rails 17 slightly overlying the slots 13 when the rails are operatively positioned transversely seated upon the top 14 of the said body. It will be understood that when the rails 17 are so arranged upon the tie, engaging beneath the ribs 15, the rails will be accurately spaced a proper distance apart for the gage of the railway line.

An angular bearing block 18 is fitted in a similarly angled slot 18' transversely of the body 14 traversing the slots 13 and secured in position by suitable pins 19. A locking latch 20 is provided for each of the slots 13 being pivoted at its lower end within the chamber 11 by means of a transverse bar 21, while the upper inner corner of each latch 20 is in the form of a hook 22 adapted for overlying the base 16 of the adjacently positioned rail 17 when the latch is inwardly tilted.

An operating screw 23 freely extends through a passage 24 in the solid end portion 25 of the body 10, such a screw being arranged for each of the blocks 18 and suitably threaded within a central opening 26 of the said blocks. A suitable head 27 is provided upon the outer end of each screw 23 within a recess 28 in the end of the body 10, one of the latches 20 being arranged within the path of movement of the adjacent screw 23.

When the device is assembled as illustrated in Fig. 4 of the drawing, a socket wrench or other implement, not shown, may be applied to the head 27 of the screw 23 for moving the screw inwardly of its bearing block 18 thereby engaging the screw against the adjacent latch 20 and forcing the latch into locking position against the base 16 of the adjacent rail 17. The rails are secured in this manner in their operative positions upon the body 10 and whenever it is desired to release a rail, the screw 23 is retracted which permits the latch 20 to be outwardly moved out of contact with the adjacent rail 17 and permitting the ready removal of the rail. A serviceable tie is provided upon

which the rails may be readily locked when desired and then easily released for removal when the occasion requires, such operations being accomplished without detaching any 5 of the holdfast members which would be liable to become lost if it was required to separate the same from the body 10. My form of tie is serviceable for laying temporary tracks such as in time of war as well as 10 tracks in mines.

What I claim as new is:—

1. A tie and rail fastener comprising an elongated body having a chamber therein with slots in the top of the body adjacent its opposite ends, transverse ribs upon the top of the body spaced inwardly of said slots a distance less than the width of the base of a railway rail, locking latches pivoted within said chamber projecting through the said slots and having inwardly projecting hooked ends arranged opposite said ribs and an inwardly moving operating means for the said latches.
2. A tie and rail fastener comprising an elongated body having a chamber therein with slots in the top of the body adjacent its opposite ends, transverse ribs upon the top of the body spaced inwardly of said slots a distance less than the width of the base of a railway rail, locking latches pivoted within said chamber projecting through the said slots, an angular bearing block fitted in a similarly angled slot transversely of said body traversing each of the said slots and an operating screw threaded through each block having a path of movement in line with the adjacently positioned latch.
3. In combination with a metallic body having a chamber therein and a longitudinal slot communicating with the said chamber and extending through the top of the

body, a rail engaging rib carried by the top of the body spaced inwardly of said slot, a swinging latch carried by the body having its upper end projecting through the said slot, a bearing block traversing said slot outwardly of the latch, the said body having a closed end outwardly of said block arranged with a recess in its outer face and a passage between said recess and chamber and a screw 50 threaded through said block and freely passing through said passage arranged with a head positioned within said recess, the said screw adapted for adjustable engagement with the said latch during the longitudinal 55 movement of the screw when the device is assembled.

4. In combination with an elongated body, a transverse rib mounted thereon, a railway rail removably positioned transversely of 60 the body engaging the said rib, a locking latch for the rail pivoted to the said body, an angular bearing block fitted in a similarly angled slot transversely of the body 65 adjacent said latch and an adjusting screw for the latch threaded through the said block.

5. A railway tie comprising a body having a slot in the top thereof, a transverse rib upon the top of the body spaced inwardly 70 from said slot, a railway rail mounted upon the body with its base overlying said slot and in contact with said rib, a latch pivoted within said slot adapted for overlying the base of the rail when the latch is inwardly 75 positioned and an adjusting screw for the latch arranged with an operating head adjacent the free end of the tie.

In testimony whereof I affix my signature.

GIOVANNI RACCAGNI.
